United States Patent Office

Des. 234,068
Patented Jan. 14, 1975

234,068

TABLE

Manus Mudde, Berkel-Enschot, Netherlands, assignor to Dart Industries, Inc., doing business as The West Bend
Company, West Bend, Wis.

Filed Jan. 22, 1973, Ser. No. 325,923

Term of patent 14 years

Int. Cl. D6—03

U.S. Cl. D6—176

FIG. 1 is a perspective view of a table embodying my new design; and

FIG. 2 is a top view thereof.

I claim:

The ornamental design for a table, substantially as shown and described.
